Primary Examiner—Antoine D. Davis(74) *Attorney, Agent, or Firm*—Guy McClung(57) **CLAIM**

The ornamental design for a support link for wellbore apparatus, as shown and described.

DESCRIPTION

FIG. 1 is a front perspective view of an access platform according to the present invention.

FIG. 2 is a rear perspective view of the access platform of FIG. 1.

FIG. 3 is a side view of the access platform of FIG. 1.

FIG. 4 is a front view of the access platform of FIG. 1.

FIG. 5 is a bottom view of the access platform of FIG. 1; and,

FIG. 6 is a top view of the access platform of FIG. 1.
